CLAIM

The ornamental design for a telescoping link, as shown and described.

DESCRIPTION

FIG. 1 is a perspective view of a telescoping link showing my new design;

FIG. 2 is a side view thereof;

FIG. 3 is another side view thereof;

FIG. 4 is another side view thereof;

FIG. 5 is another side view thereof;

FIG. 6 is an end view thereof;

FIG. 7 is an opposite end view thereof;

FIG. 8 illustrates the telescoping link with the link partially extended from the housing; and,

FIG. 9 illustrates the telescoping link with the link fully extended from the housing.
